(57) **CLAIM**

I claim the ornamental design for a hearing aid eartip, as shown and described.

DESCRIPTION

FIG. 1 illustrates a perspective view a hearing aid eartip showing my new design;

FIG. 2 illustrates a side view of the hearing aid eartip;

FIG. 3 illustrates an end view of the hearing aid eartip; and,

FIG. 4 illustrates a side sectional view of the hearing aid eartip.

1 Claim, 4 Drawing Sheets
